UNITED STATES PATENT OFFICE.

ERNEST M. KLUCK, OF BUFFALO, NEW YORK, ASSIGNOR OF ONE-HALF TO HIMSELF
AND ONE-HALF TO NICHOLAS C. NEWERF, OF BUFFALO, NEW YORK.

AUTOMOBILE-RADIATOR.

1,101,080.

Specification of Letters Patent. Patented June 23, 1914.

Application filed February 9, 1911. Serial No. 607,587.

To all whom it may concern:

Be it known that I, ERNEST M. KLUCK, a citizen of the United States, residing at Buffalo, in the county of Erie and State of 5 New York, have invented new and useful Improvements in Automobile-Radiators, of which the following is a specification.

This invention relates to improvements in radiators for automobiles and the like.

10 One of the features of the invention has reference to the construction of the cooling element which is provided with a series of independent cooling sections, any one of which may be removed from the remainder 15 of the radiator for repair or replacement without in any way disturbing the other sections or dismounting the radiator.

Another feature of the invention has reference to the peculiar oblique arrangement 20 of the deflecting portions of the fins whereby a more efficient and uniform cooling effect is produced.

The principal objects of the invention are 25 to provide a radiator in which the cooling sections may be quickly removed and replaced, and in which air is deflected tangentially to increase the cooling effect.

The invention also relates to certain details of construction which will be herein- 30 after described and claimed, reference being had to the accompanying drawings in which a preferred adaptation of the improved radiator is shown.

Figure 1 represents the improved radiator 35 partially in front elevation and partially in section, two vertical sections being taken through the radiator on different lines to show the internal construction. Fig. 2 is an end or edge elevation of the improved radiator. Fig. 3 is an enlarged fragmentary section taken vertically on line *a-a*, Fig. 1, through the improved radiator. Fig. 4 is an enlarged 40 transverse horizontal section through the tubes of one of the cooling sections of the radiator showing a plan view of one of the fins. Fig. 5 is an enlarged side elevation of a fragment of one of the cooling sections of the radiator. Fig. 6 is an enlarged 45 vertical section of a fragment of one of the fins on line *b-b*, Fig. 4. Fig. 7 is an enlarged fragmentary horizontal section on line *c-c*, Fig. 2, showing the manner of securing the 50 end plate to the tie rods by means of flanged

collars, a transverse section also being 55 shown through two of the tie rods.

In referring to the drawings in detail, like numerals designate like parts.

The adaptation of the improved radiator shown in Figs. 1, 2 and 3 consists of an upper tank 1, for the water or other cooling medium, a lower tank 2 for the water or other cooling medium, and a series of independent cooling sections fitted in interposed position between the upper and lower 60 tanks, said independent cooling sections being connected at their respective ends to said upper and lower tanks for the circulation therethrough of the water or other cooling medium. The cooling sections are 65 removably attached at their respective upper and lower ends to the upper and lower tanks by means of curved connections which fasten to the front of the tanks so that the sections when unfastened may be easily and 70 quickly removed by simply drawing them forward out of place in the radiator.

The cooling sections are identical in construction so that one may be readily substituted for another, and for this reason a 80 detailed description of the construction of one of the sections will suffice for all.

Each of the cooling sections comprises an upper hollow element or header 3, a lower hollow element or header 4, a series of vertical 85 circulating tubes 5 extending between and connecting said hollow elements, and a multiplicity of horizontal heat radiating fins 6 disposed at regular intervals and having openings through which the vertical 90 tubes 5 pass. The upper hollow element or header of each section is substantially rectangular in cross-section, as shown in Fig. 1, and practically constitutes a small supplementary upper chamber for the cooling 95 medium, which when the section is in place in the radiator is located directly beneath the upper tank 1. A tubular extension 7 curves forward and upward, and has its upper end provided with an outwardly ex- 100 tending flange 8 through which screws 9 are adapted to be fitted to detachably secure the tubular extension to the upper tank 1, as shown in Figs. 2 and 3, particularly Fig. 3. A suitable packing 10 is fitted between the 105 upper end of the tubular extension 7 and the front face of the upper tank 1 to insure a tight joint. The upper tank 1 has on its

front face a plurality of openings 11, each of which registers with the upper end of one of the tubular extensions 7. The lower hollow element or header 4 of each section 5 is likewise substantially rectangular in cross-section, and constitutes a small supplementary lower chamber for the cooling element. Said lower hollow element 4 is provided with a curved tubular extension 12 10 which curves downward, and has its lower end detachably fastened to the front face of the lower tank 2. The front face of the lower tank 2 is likewise provided with a series of openings 13 which are equal in 15 number to the cooling sections, and each of which is adapted to register with the lower end of one of the lower tubular extensions 12, as shown in Fig. 1.

The means for fastening the lower tubular extensions 12 to the lower tank 2 is 20 slightly different from that employed in connection with the upper tubular extensions, heretofore described, a series of lock strips 14 being used, each of which is fastened to the front of the lower tank by a 25 single screw 15. Each of the lock strips 14 has its respective ends lapping over the side margins or flanges of the lower tubular extensions 12, as shown in Fig. 1. However, if it is desired, either of the fastening 30 means described may be used, or other suitable means may be employed in lieu thereof to detachably fasten the sections in place.

The circulating tubes 5 are of oblong form 35 in cross-section, as shown in Figs. 4 and 7, and extend in a straight vertical direction from the upper hollow element to the lower hollow element, their upper ends being fitted and secured in openings in the bottom 40 wall of the upper hollow element, and their lower ends being fitted and secured in openings in the top wall of the lower hollow element, as shown in Figs. 1 and 3. The hollow extensions or continuations 7 and 12 of 45 the hollow elements or headers have curved openings therethrough of approximately the same area throughout, see Figs. 1 and 3, each of which gradually changes from a rectangular form at its merging point with 50 the tubular header which is similar in size and shape to the opening in the tubular header to a circular form at its marginally flanged rear end which is equal in diameter to the circular openings in the front of the 55 water tanks. Furthermore, the gradual change from a rectangular form to a circular form prevents the formation of dead pools or quiet places for the circulating water, where freezing is most likely to occur in cold weather. All water in the radiator 60 is thus kept constantly moving, and a substantially even temperature throughout the mass of water or other cooling fluid is thus maintained.

65 The heat radiating fins are preferably

made of a good heat-conducting metal, and preferably are formed or stamped of thin sheet metal and substantially to the shape shown in Figs. 4, 5 and 6. Each of the fins is provided with oblong openings 70 through which the conducting tubes 5 pass, as shown in Fig. 4, and a series of substantially triangular openings 17 which are located between the oblong openings, being arranged in straight rows between the 75 straight rows of the oblong openings through which the tubes 5 pass. The triangular openings 17 are formed by cutting straight slits in the metal of the fin, which extend in a direction transversely to the radiator, 80 and straight slits which extend forward from the center of the transverse slits at a right angle to said transverse slits. The two projecting portions 18 and 19 formed by thus slitting the metal of the fin, are bent 85 downward and away from each other sufficiently to extend or project in the path of the air currents passing through the radiator when the automobile is traveling, and form air deflecting portions. The air thus 90 deflected, strikes against the adjacent surface of the next plate or passes through the openings therein, so that the air encountered by the first is made, as it were, to do double duty. These portions 18 and 19 95 are not bent sufficiently to be at right angles with the remainder of the fin, but only so as to extend in a direction oblique to the plane of the fin, and diagonally with respect to the direction of the air currents 100 which pass through the radiator, so that the air currents in passing through impinge on the surface of the said portions, and are thereby deflected diagonally downward and also laterally toward the conducting tubes 5, 105 thus producing a better and more efficient cooling action.

It will be noted by referring to Figs. 4 and 5 that the deflecting portions 18 and 19 progressively increase in size from the 110 front to the rear of the fin. The advantage of this construction is that the air as it passes through the radiator, successively impinges on the deflecting portions, and is thus deflected toward all of the tubes, thereby producing a highly efficient air cooling effect. The upper and lower tanks 1 and 2 are respectively provided with short tubular connections 20 and 21, as shown in Figs. 2 and 3 for the attachment of pipes leading 115 to the water jacket of the motor of the automobile. The radiator is provided with end plates 22 and 23, which are fitted flush with the ends of the upper and lower tanks 1 and 2, as shown in Fig. 1, and serve to 120 give a finished appearance to the ends of the radiator. These end plates are each supported from a pair of vertical tie rods 24 and 25 by means of upper and lower flanged collars 26 and 27. As two tie rods 125

are employed at each end of the radiator, two upper and two lower collars are necessarily required, as shown in Figs. 1, 2 and 7. These collars are fastened to the plates by rivets 28 and are fitted around the tie rods, as shown in Fig. 7. The upper and lower ends of the tie rods respectively pass through eyes in lugs 29 and 30 which extend from the upper and lower tanks 1 and 2. Nuts 31 and 32 are screwed on the respective upper and lower ends of the rods and serve to fasten the component parts or elements of the radiator together. The radiator is yieldingly supported from the frame of the automobile, being balanced on springs mounted in brackets attached to the automobile frame. Two of these brackets are employed, one being located at each end of the radiator, and being fastened rigidly to the automobile frame by rivets or other suitable fastenings 33. In construction, each of these brackets has a horizontal member 34, the outer end portion of which is secured by a rivet to the frame of the automobile, and two parallel vertical members 35 and 36, each of which is provided with upper and lower inwardly extending eyes 37 and 38 through which the tie rods loosely pass. Centrally located collars 39 are also provided through which the tie rods pass, said collars being fastened to the tie rods by means of set screws 40, as shown in Fig. 1. Upper and lower springs 41 and 42 are respectively interposed between the central collars 39, and the upper and lower eyes 37 and 38. By this means, the radiator is yieldingly balanced against vertical movement in either direction, so that a large portion of the shocks transmitted to the frame of the automobile is absorbed by the springs and is prevented from reaching the radiator. The upper tank 1 is provided with a filling tube 43 having a removable cap 44 which is secured in place by a set screw 45, as shown in Figs. 1 and 2.

The advantages of this improved radiator reside in the unique separable unit construction of the radiator, in the peculiar shape and formation of the cooling fins, and in the spring mounting of the radiator on the automobile frame. It will be noted that the cooling sections are absolutely independent and that any one of them may be removed by simply disconnecting it from the upper and lower tanks and drawing it forward out of place in the radiator. Should one of these cooling sections leak, it may be easily removed and the round openings in the upper and lower tanks easily closed by corks, thus enabling the operator to run the automobile until a place is reached where a proper repair may be made.

I claim:

1. In a radiator of the class described, upper and lower water tanks in separated ar-

rangement, each having a flat vertical front surface provided with a series of circular openings and a series of independent removable cooling sections arranged between said upper and lower water tanks; each of said cooling sections consisting of a series of vertical conducting tubes in separated arrangement, a plurality of horizontal cooling fins disposed at intervals on said conducting tubes, upper and lower tubular headers to which the upper and lower ends of the vertical conducting tubes are respectively connected and hollow continuations curving outwardly from the front ends of the upper and lower headers and then inwardly and having marginally flanged rear ends which fit against the margins of the circular openings in the front of the water tanks; the opening through each of the hollow continuations gradually changing from a rectangular form at its merging point with the tubular header to a circular form at its marginally flanged rear end.

2. In a radiator of the class described, upper and lower water tanks in separated parallel arrangement, each of said tanks having a flat vertical front surface provided with a series of circular openings and a series of independent removable cooling sections arranged between said upper and lower water tanks and each consisting of a series of vertical conducting tubes in separated arrangement, a plurality of horizontal cooling fins disposed at intervals on said tubes, upper and lower tubular headers to which the upper and lower ends of the vertical conducting tubes are respectively connected and hollow continuations curving outwardly from the front ends of the upper and lower headers and then inwardly and having marginally flanged rear ends which fit against the margins of the circular openings in the front of the water tanks and the opening through each of the hollow continuations gradually changing from a rectangular form at its merging point with the tubular header and similar in size shape and area to the opening in the tubular header to a circular form at its marginally flanged rear end of equal diameter to the circular openings in the front of the water tanks and said opening through the hollow continuation being of approximately the same area throughout.

3. In a radiator of the class described, upper and lower water tanks in separated arrangement, each having a front surface provided with a series of openings, and a series of independent removable cooling sections arranged between said upper and lower tanks; each of said cooling sections consisting of a series of vertical conducting tubes in separated arrangement, a plurality of horizontal cooling fins disposed at intervals on said conducting tubes, upper and

- lower headers of tubular form to which the upper and lower ends of the vertical conducting tubes are respectively connected and hollow continuations curving outwardly 5 from the front ends of the upper and lower headers and then inwardly and having marginally flanged rear ends which fit against the margins of the openings in the front of the water tanks, and means for detachably 10 fastening the cooling sections in place.
4. In an automobile radiator, upper and lower tanks, vertical radiator sections extending between said tanks, said sections 15 each having flat tubes and perforated metal plates or fins fitting thereover, said plates or fins between the tubes having parts bent up, and all pointing rearward to deflect air currents obliquely against succeeding plates.
5. In an automobile radiator, upper and 20 lower tanks, vertical radiator sections extending between said tanks, said sections each having flat tubes and perforated metal plates or fins fitting thereover, said plates or 25 fins between the tubes having parts bent up and all pointing rearward to deflect air currents obliquely against succeeding plates, said bent up portions being in line from front to rear.
6. In an automobile radiator, upper and 30 lower tanks, vertical radiator sections extending between said tanks, said sections each having flat tubes and perforated metal

plates or fins fitting thereover, said plates or fins between the tubes having parts bent 35 up and all pointing rearward to deflect air currents obliquely against succeeding plates, said bent up portions increasing in size from front to rear.

7. In an automobile radiator, upper and 40 lower tanks, vertical radiator sections extending between said tanks, said sections each having flat tubes and perforated metal plates or fins fitting thereover, said plates or fins between the tubes having parts bent 45 up and all pointing rearward to deflect air currents obliquely against succeeding plates, said bent up portions being arranged symmetrically on each side of a central line.

8. In an automobile radiator, upper and 50 lower tanks, vertical radiator sections extending between said tanks, said sections each having flat tubes and perforated metal plates or fins fitting thereover, said plates or fins between the tubes having parts bent 55 up, all pointing rearward to deflect air currents obliquely against succeeding plates, said bent up portions being arranged in pairs, and each pair forming a tent-shaped opening facing rearward.
